US0D1109592S

(12) **United States Design Patent** (10) Patent No.: **US D1,109,592 S**
(45) Date of Patent: ** Jan. 20, 2026

(54) **BRACKET APPLIED TO A WINDOW TREATMENT**

(71) Applicant: **Lutron Technology Company LLC**,
Coopersburg, PA (US)

(72) Inventor: **Vladislav Pejic**, Allentown, PA (US)

(73) Assignee: **Lutron Technology Company LLC**,
Coopersburg, PA (US)

(**) Term: **15 Years**

(21) Appl. No.: **29/985,231**

(22) Filed: **Jan. 16, 2025**

Related U.S. Application Data

(63) Continuation of application No. 29/914,468, filed on Oct. 18, 2023, which is a continuation of application No. 29/882,054, filed on Jan. 10, 2023, now Pat. No. Des. 1,005,831, which is a continuation of application No. 29/776,598, filed on Mar. 31, 2021, now Pat. No. Des. 976,089, which is a continuation of application No. 29/774,353, filed on Mar. 16, 2021, now Pat. No. Des. 947,659, which is a continuation of application No. 29/730,937, filed on Apr. 9, 2020, now Pat. No. Des. 916,583, which is a continuation of application No. 29/616,079, filed on Sep. 1, 2017, now Pat. No. Des. 883,776.

(57) **CLAIM**
The ornamental design for a bracket applied to a window treatment as shown and described.

DESCRIPTION

FIG. 1 is a perspective view of a bracket applied to a window treatment showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the bracket applied to a window treatment which form no part of the claimed design. The drawings include CAD lines which represent contour and not surface ornamentation.
